UNITED STATES PATENT OFFICE.

GEORGE H. CHARNOCK, OF BUFFALO, NEW YORK.

SILENCER FOR GAS-ENGINE-VALVE MECHANISM.

Application filed February 6, 1923. Serial No. 617,360.

To all whom it may concern:

Be it known that I, GEORGE H. CHARNOCK, a citizen of the United States, residing at Buffalo, in the county of Erie and State of New York, have invented new and useful Improvements in Silencers for Gas-Engine-Valve Mechanism, of which the following is a specification.

This invention relates to a device for taking up the slack in the operating mechanism of an overhead gas engine valve at a point outside of the crank case or lower enclosed part of the engine frame, so that any noise which is produced when the parts become worn will not be audible and thus render the operation of the engine more pleasant and satisfactory.

It is the purpose of this invention to provide simple and efficient means whereby the slack in this type of valve operating mechanism is taken up automatically between the rock lever of each valve and the corresponding push rod which is actuated by a cam, the structure being such that the same can be applied to overhead valve gas engines without requiring any change in the construction of the valve mechanism as now found on the market.

In the accompanying drawings:

Figure 1 is a fragmentary vertical section of an internal combustion engine having its valve mechanism equipped with my invention. Figures 2 and 3 are perspective views of the yoke and coupling block forming part of the take-up device containing my improvements. Figure 4 is a fragmentary top plan view of the engine embodying my improvements. Figure 5 is a fragmentary view, on an enlarged scale, of those portions of the valve mechanism immediately adjacent to where the rocker arm, push rod and valve stem come together. Figures 6 and 7 are horizontal sections taken on the correspondingly numbered lines in Fig. 5.

Similar characters of reference indicate corresponding parts throughout the several views.

This invention is applicable to gas engines which may vary as to details of construction, that shown in the drawings, being merely typical of one in which my invention can be used to advantage. As shown, this engine comprises a body or frame containing an upright cylinder 6, a head 7 at the top of the cylinder, and a piston 8 reciprocating vertically in the cylinder and

having its connecting rod 9 coupled with the crank of the driving shaft in any way suitable and well known manner.

With each cylinder is associated a valve mechanism comprising a fuel inlet valve and an exhaust valve by means of which live gaseous fuel is admitted to the cylinder and the products of combustion are discharged therefrom. The inlet and exhaust valves are operated respectively by means which comprise rock levers 10, 11, and as the mechanism associated with the inlet and exhaust valves is identical in construction, the following description relating to the mechanism for operating the inlet valve 12, will, so far as it applies, also serve to describe the mechanism for operating the exhaust valve.

The inlet valve 12 is of the usual circular outwardly tapering form and adapted to move vertically toward and from a valve seat 13 arranged around the inner end of the fuel inlet or passage 14 in the head of the body. On its upper side this valve is provided with a vertical valve stem 15 which extends to the exterior of the body and has its intermediate part guided in a sleeve 16 mounted in the upper part of the head.

Each of the valves is yieldingly held in its upper closed position by a collar 17 preferably of cap shaped form mounted on the upper part of each valve stem and engaging its upper side with a shoulder 18 formed by a washer 19 interlocking with the valve stem, and a helical spring 21 surrounding the valve stem and engaging its lower end with the guide sleeve 16 and its upper end with the underside of said collar, as shown in Figs. 1, 2 and 3.

The inlet and exhaust valve rock levers are pivotally supported side by side on a shaft 22 mounted on the top of the head and the inlet valve rock lever has its rocker arm 23 arranged over the upper end of the stem of the inlet valve while its tail 25 is provided with a downwardly opening socket 24 which receives the spherical knuckle 26 at the upper end of an upright push rod 27. The knuckle 26 has a screw connection with the push rod so that the same can be adjusted lengthwise therein by hand for taking up slack in the valve operating mechanism and after such adjustment has been effected, the knuckle is held in position by a clamping screw nut 20 arranged on the

push rod and engaging the lower end of the knuckle. In the lower part of the engine frame or body is rotatably mounted the valve shaft 28 which is provided with a rotary cam 18 engaging the lower end of a vertical tappet 29. The latter slides in a guide sleeve 30 on the lower part of the body or frame and transmits a lifting movement to the push rod through the medium of a ball 31 interposed between the ball sockets 32, 33, formed on the opposing ends of the tappet and push rod, as shown in Fig. 1. As the high part of the cam engages the tappet, the rock lever is turned in the direction for depressing and opening the valve and when the low part of this cam is presented to the tappet, the spring 21 is permitted to close the valve.

Ordinarily, the underside of the rocker arm is set so close to the upper end of the valve stem by means of the band operable adjusting device between the tail 25 and the push rod 27, that the rocker arm and stem barely touch.

When wear occurs in the valve operating mechanism, the distance between the rocker arm and the valve stem increases and this causes the rocker arm to engage the valve stem with a noisy click or tap which is not only annoying but also produces rapid wear on the co-operating surfaces. To avoid this, means are provided for constantly pulling upwardly on the push rod so as to hold the knuckle at its upper end in engagement with the tail of the rock lever and the rocker arm of the latter is in constant engagement with the upper end of the valve stem, thereby transferring any looseness or slack in the valve operating mechanism to the ball joint between the push rod and tappet and the opposing surfaces of the tappet and the cam, which places are located within the body, frame or casing of the engine where the same are almost, if not entirely suppressed, and therefore do not cause any annoyance.

The preferred form of my invention for accomplishing this purpose is constructed as follows:

34 represents a yoke of U-shaped form which has its legs 35 straddling the push rod and bearing with its cross piece 36 against one side of the push rod. The top of the yoke engages with the underside of the screw nut 20 which latter in effect is part of the knuckle 26 and practically forms a downwardly-facing shoulder on the latter. The distance between the legs of the yoke is equal to the diameter of the push rod, so that the latter will fit snugly in the yoke when these parts are assembled. Adjacent to the extremities of the legs of the yoke the same are provided on their inner opposing sides with two concave seats 37 which are arranged concentrically relatively to

each other and in effect produce an enlargement of the space between the legs of the yoke on that side of the push rod opposite to where the latter is engaged by the cross piece of the yoke. Removably arranged between the legs of the yoke on that side of the push rod opposite the cross piece of the yoke and engaging with the seats 37 thereof is the upper reduced part 38 of a coupling block which part is of cylindrical form to fit said seats. Below its upper part said coupling block is provided with an enlarged lower part 39 forming an upwardly facing shoulder 40 between said parts which engages with the underside of the yoke. The latter is detachably connected with the coupling block by a cotter pin 41 passing transversely through corresponding openings in the yoke legs and the upper reduced part of the coupling block. The upper part of the coupling block fits closely against the push rod and the lower enlarged part of the same is provided with a curved recess 42 on its side which receives the adjacent part of the push rod, thereby securely holding the yoke, block and push rod against lateral movement relatively to each other and avoiding any rattling noise during the operation of the valve mechanism. The provision of the recess 42 in the block also ensures assembling the parts in a definite manner inasmuch as the block cannot be inserted into the yoke unless the recess of the same faces the push rod, thus always bringing the openings of the coupling block and the yoke into the proper position to receive the cotter pin 41.

The coupling block, yoke and push rod are yieldingly pulled upwardly by means which comprise a helical take-up spring 43 connected at its lower end with the outer side of the coupling block by means of a screw 44, or otherwise, while its upper end is secured to a fixed support which in the present instance consists preferably of a horizontal supporting rod 45 arranged lengthwise over the engine body. The supporting rod is preferably carried at suitable places by brackets 46 secured to the same standards 47 on which the shaft of the valve rock levers are mounted. The tension of the spring 43 operates to constantly draw the push rod upwardly against the tail of the rock lever and press the rocker arm of the lever downwardly against the valve stem so as to prevent any slack or lost motion between these parts, but this spring is weaker than the main valve spring 21, so as to ensure closing of the valve at the proper time under the action of the last mentioned spring.

By this means, the possibility of looseness between the exposed moving parts of the valve mechanism is eliminated and as a result these parts will not produce any tapping action or other objectionable noise, but

instead any slack or lost motion in the working parts will be concentrated at the joint between the tappet and push rod and between the cam and tappet, the location of 5 which is inside of the engine body and therefore no noise made by the same would be perceptible.

Aside from rendering the operation of the valve mechanism noiseless, this device 10 will automatically take up any wear on the external parts of the valve mechanism and thus avoid the necessity of frequently taking up such wear by means of manual adjustment of the parts.

15 Moreover, this improved take up device is of such a construction that the same can be readily and quickly applied to the standard forms of engines now on the market without any alteration in the same. Owing 20 to the simplicity of the device, the same can be produced at very small cost and as it contains no delicate parts the same is not liable to get out of order.

I claim as my invention:

25 1. A valve mechanism for gas engines comprising a rock lever having a rocker arm adapted to operate a valve and a tail provided with a socket, a push rod adapted to be actuated by a cam and provided 30 with a knuckle engaging with said socket and forming a shoulder on said rod, and means for yieldingly holding said knuckle in engagement with said socket comprising a yoke of U-shaped form engaging 35 with the underside of said head and having its legs straddling said rod, and its cross bar engaging one side of the rod, a coupling block arranged between the legs of the yoke, and a spring connected at one 40 end with said block and at its other end with said tail.

45 2. A valve mechanism for gas engines comprising a rock lever having a rocker arm adapted to operate a valve and a tail provided with a socket, a push rod adapted to be actuated by a cam and provided with a knuckle engaging with said socket and forming a shoulder on said rod, means for yieldingly holding said knuckle in engagement with said socket comprising a yoke of 50 U-shaped form engaging with the underside of said head and having its legs straddling said rod and its cross bar engaging one side of the rod, a coupling block arranged between the legs of the yoke and engaging 55 with the opposite side of said rod, and a spring connecting at one end with said block and at its other end with said tail.

60 3. A valve mechanism for gas engines comprising a rock lever having a rocker arm adapted to operate a valve and a tail provided with a socket, a push rod adapted to be actuated by a cam and provided with a knuckle engaging with said socket and forming a shoulder on said rod, and means

for yieldingly holding said knuckle in engagement with said socket comprising a yoke of U-shaped form engaging with the underside of said head and having its legs straddling said rod and its cross bar engaging one side of the rod, a coupling block arranged between the legs of the yoke and engaging with the opposite side of said rod, and having an upper reduced part which is secured between the legs of said yoke and a lower enlarged part bearing against the underside of said yoke, and a spring connected at one end with said coupling block and at its other end with said tail.

4. A valve mechanism for gas engines comprising a rock lever having a rocker arm adapted to operate a valve and a tail provided with a socket, a push rod adapted to be actuated by a cam and provided with a knuckle engaging with said socket and forming a shoulder on said rod, and means for yieldingly holding said knuckle in engagement with said socket comprising a yoke of U-shaped form engaging with the underside of said head and having its legs straddling said rod, and its cross bar engaging one side of the rod, a coupling block arranged between the legs of the yoke and detachably connected therewith, and a spring connected at one end with said block and at its other end with said tail.

5. A valve mechanism for gas engines comprising a rock lever having a rocker arm adapted to operate a valve and a tail provided with a socket, a push rod adapted to be actuated by a cam and provided with a knuckle engaging with said socket and forming a shoulder on said rod, and means for yieldingly holding said knuckle in engagement with said socket comprising a yoke of U-shaped form engaging with the underside of said head and having its legs straddling said rod, and its cross bar engaging one side of the rod, a coupling block arranged between the legs of the yoke, and a pin passing through said yoke and block, and a spring connected at one end with said block and at its other end with said tail.

6. A valve mechanism for gas engines comprising a rock lever having a rocker arm adapted to operate a valve and a tail provided with a socket, a push rod adapted to be actuated by a cam and provided with a knuckle engaging with said socket and forming a shoulder on said rod, and means for yieldingly holding said knuckle in engagement with said socket comprising a yoke of U-shaped form engaging with the underside of said head and having its legs straddling said rod and its cross bar engaging one side of the rod, a coupling block arranged between the legs of the yoke, a spring connected at one end with said block, and at its other end with said tail.

and a stationary rod connected with the other end of said spring.

7. A valve mechanism for gas engines comprising a rock lever having a rocker arm adapted to operate a valve and a tail provided with a socket, a push rod adapted to be actuated by a cam and provided with a knuckle engaging with said socket and forming a shoulder on said rod, and means for yieldingly holding said knuckle in engagement with said socket comprising a yoke of U-shaped form engaging with the underside of said head and having its legs straddling said rod and its cross bar engaging one side of the rod, a coupling block engaging with the opposite side of said rod and having an upper reduced part which is secured between the legs of said yoke and a lower enlarged part bearing against the underside of said yoke and having a recess on its inner side which receives the adjacent part of said push rod, and a spring connected with said coupling block.

8. A take-up device for gas engine valve mechanism comprising a U-shaped yoke adapted to straddle a push rod and bear against a shoulder thereon, a coupling block

secured between the legs of said yoke and engaging the adjacent side of said rod, and a spring for lifting said coupling block and yoke.

9. A take-up device for gas engine valve mechanism comprising a U-shaped yoke adapted to straddle a push rod and bear against a shoulder thereon, and provided on the inner sides of its legs with opposing recesses, a coupling block secured in the recesses of said legs and engaging the adjacent side of said rod, and a spring for lifting said block and yoke.

10. A take-up device for gas engine valve mechanism comprising a U-shaped yoke adapted to straddle a push rod and bear against a shoulder thereon and provided on the inner sides of its legs with opposing recesses, a coupling block having a reduced upper part which is detachably secured to said legs within the recesses thereof and engages with the adjacent side of said rod and an enlarged lower part which is provided on its side with a recess adapted to receive said push rod, and a spring for lifting said coupling block and yoke.

GEORGE H. CHARNOCK.
